DESIGN FOR A MOVING PICTURE CAMERA

Philmore F. Sperry, Chicago, Ill., assignor to
Excell Auto Radiator Company, Chicago, Ill., a
corporation of Delaware

Application August 26, 1938, Serial No. 79,575

Term of patent 14 years

To all whom it may concern:

Be it known that I, Philmore F. Sperry, a citizen of the United States, residing at Chicago, in the county of Cook and State of Illinois, have invented a new, original, and ornamental Design for a Moving Picture Camera, of which the following is a specification, reference being had to the accompanying drawing, forming part thereof, in which

Fig. 1 is a side face view of a camera embodying my design;

Fig. 2 is a front face view of the camera;
Fig. 3 is a top plan view of the camera; and
Fig. 4 is a side face view of the camera from the opposite side as compared with the showing of Fig. 1.

I claim:
The ornamental design for a moving picture camera, as shown.

PHILMORE F. SPERRY.

CERTIFICATE OF CORRECTION.
